CLAIM

The ornamental design for a cutter as shown and described.

DESCRIPTION

FIG. 1 is a perspective view of a cutter, showing the new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side view thereof.

The shading lines shown in the drawings represent the approximate three-dimensional contour of the design, and are not intended to indicate surface decoration.

The broken line(s) shown in the drawings illustrate portions of the cutter that form no part of the claimed design.
